UNITED STATES PATENT OFFICE.

WILLIAM McCONWAY, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR COUPLER.

Application filed August 7, 1925. Serial No. 48,898.

The invention relates to car couplers of the Master Car Builders' type, and has for its object to afford an efficiently operating mechanism consisting of simple and durable parts which may be readily assembled.

The primary feature of the invention consists in providing the coupler with a lock lifter which also serves to prevent accidental unlocking of the lock, the lifter and lock being operatively connected so as to be capable of sliding and swinging movements with respect to each other, and the lock when moved to unlocked position by the lifter being adapted under the influence of gravity to swing over and be supported in unlocked position by the tail of the knuckle, thereby enabling the rotatable knuckle to be subsequently opened.

A further feature of the invention involves the provision, in combination with a coupler head, a knuckle rotatably mounted thereon, and a lock for said knuckle, of a lock lifter provided intermediate its ends with a slot which is inclined to the direction of unlocking movement of the lock and which receives a pivot pin carried by the lock, the pivot pin being positioned forward of the center of gravity of the lock so as to cause the lower end of the latter to swing forwardly toward the tail of the knuckle when the lifter moves the lock to unlocked position, thereby enabling the lock to be supported in unlocked position on the tail of the knuckle while the latter is closed, and the lifter being formed with a shoulder or projection for cooperating with the coupler head to prevent the lock from accidentally moving to unlocked position.

A still further feature of the invention consists in movably connecting the lock and its lifter by a pin and slot construction in which the pin is provided with a head and the lock is furnished with means for cooperating therewith to retain the pin in its assembled position.

Other features of the invention, relating to advantageous forms of construction and combinations of elements, will hereinafter appear.

In the drawings illustrating a preferred embodiment of the invention, the scope whereof is pointed out in the claims:

Figure 1 is a view, partly in side elevation and partly in vertical section, of a

car coupler embodying the invention, the parts being in normal locked relation.

Figure 2 is a plan view of a portion of the mechanism shown in Fig. 1.

Figure 3 is a detail sectional view on the line 3—3, Fig. 1, showing the lock and its lifter, the pivot pin connecting these parts being shown in plan.

Figure 4 is a view, partly in front elevation and partly in transverse vertical section, the parts being in locked relation.

Figure 5 is a detail view, partly in elevation and partly in vertical section, showing the lock supported in lock set position.

Figure 6 is a detail view corresponding to Fig. 5 but illustrating the lock as having performed an extended unlocking movement for actuating the knuckle opener lever.

Figure 7 is a detail sectional view on the line 7—7, Fig. 2.

In the drawings, 1 is the coupler head and 2 is the knuckle which, as is customary, is rotatably connected to the head by means of a knuckle pin 3. Outward rotation of the knuckle to uncoupled position is normally restrained by a vertically movable gravity actuated lock 4 which, when in locked position, extends into the path of uncoupling movement of the tail 5 of the knuckle.

The lock 4 is moved to unlocked position by means of a lifter or lock actuating member 6, the upper portion of the lock preferably being cored out to receive said lifter.

The lifter 6 and lock 4 are connected so as to be capable of relative sliding and pivotal or tilting movements. To effect this movable connection the lifter 6 may advantageously be fashioned intermediate its ends with a slot 7 which is inclined with respect to the direction of unlocking movement of the lock 4. A pin 8, carried by the lock, extends through the slot 7 of the lifter.

This pin is located forwardly of the vertical line passing through the center of gravity of the lock 4, and it therefore results, as shown in Fig. 5, that the lower end of the lock swings or tilts forwardly toward the tail of the knuckle when the lifter 6 has been actuated to cause the lock to assume unlocked position.

To allow this tilting action to take place the rear face of the lock 4 is formed with a suitable recess or depression 9.

The pin 8 by which the lock and its lifter

are connected is preferably provided with a head 10 which extends at right angles to the body or pivot portion of the pin. To receive this pin the lock 4 is provided at its 5 upper end with a perforated web or wall 11 which extends between and is in spaced relation to the side walls of the lock. The lock side wall 12, which is adjacent the knuckle, is perforated in alinement with the 10 opening in the wall 11 so as to receive the pin 8. The lock side wall 13 adjacent the guard arm of the coupler is provided with a slot 14 which extends upwardly above the pivot pin openings in the walls 11 and 12 of 15 the lock, said slot being of sufficient length to permit the bent end 10 of the pin to pass therethrough. In assembling the mechanism the head 10 of the pin after having been passed through the vertical opening 14 20 is rotated so that it stands on the inside of and in overlapping relation to the side wall 13 of the lock. The pin 8 is thereby maintained in place.

In addition to acting as a means for moving the lock to unlocked position, the lock lifter 6 serves to prevent the lock from accidentally moving to unlocked position while the coupler is in service and also affords means for actuating a pivoted knuckle 25 opener lever 15 by which the knuckle 2 is rotated to uncoupled position. For the purpose of preventing the lock from accidentally moving to unlocked position as a result of shocks and jars incident to service the lifter 6 is formed with a forwardly projecting lug or shoulder 16 which, when the lock 4 is in locked position, normally extends under an adjacent portion 17 of the top wall of the coupler head. To enable the shoulder 30 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 head to prevent accidental unlocking of said lock and having a slot for receiving said pin, said slot extending at an angle to the direction of unlocking movement of said lock, 5 said lock being provided with spaced walls perforated to receive said pin and being provided with a side wall having an opening through which the head of said pin is adapted to pass when in a given position, and the head of said pin when the parts are assembled being disposed inwardly of said side wall and in overlapped relation to the latter.

2. A car coupler involving a coupler head, a knuckle rotatably mounted thereon, a lock 15 for the knuckle, a lock lifter for moving the lock to unlocked position, and a pivotally mounted knuckle opener lever having a portion which overlaps said lock, the lifter and lock being movably connected so as to be 20 capable of relative sliding and tilting movements, the lifter having a shoulder for cooperating with the coupler head to prevent accidental unlocking of the lock, and also having a portion projecting beyond the lock 25 for engaging and actuating the knuckle opener lever, the lock when moved to unlocked position by said lifter being adapted to tilt with respect to the latter so as to assume a position in which it is supported in 30 unlocked position while the knuckle is closed, and the shoulder and the projecting portion of the lifter being substantially in the same vertical plane.

3. A car coupler involving a coupler head, a knuckle rotatably mounted thereon, a lock for said knuckle, and a lock lifter for moving the lock to unlocked position, the lifter being formed with a shoulder for cooperating with the coupler head to prevent accidental unlocking of the lock, said lifter and lock being movably connected so as to be 40 capable of relative sliding and tilting movements, the lock when moved to unlocked position by the lifter being adapted to tilt to

a position in which it is supported in unlocked position on the tail of the knuckle while the knuckle is closed, and the rear face of the lock being recessed to permit said tilting of the lock when the latter is moved to unlocked position by the lifter. 45

4. A car coupler involving a coupler head, a knuckle rotatably mounted thereon, a lock for said knuckle, a lock lifter for moving the lock to unlocked position, and a knuckle opener lever rotatably mounted on the coupler head so as to swing transversely with respect to the latter, one arm of the knuckle opener lever overlapping the forward face of the lock and the knuckle engaging portion of the other arm of said lever being offset forwardly, the lifter and lock being movably connected to permit the lower end of the lock to swing forwardly and be supported in unlocked position on the tail of the knuckle while the latter is closed, and the lifter being formed with a portion which projects beyond the forward face of the lock and is adapted to engage and actuate the knuckle opener lever. 50

5. A car coupler involving a coupler head, 70 a knuckle rotatably mounted thereon, a lock for the knuckle, a knuckle opener lever pivotally mounted on the coupler head, and means for operatively connecting the lock and lifter so as to permit them to have relative sliding and tilting movements, the tail of said knuckle being provided at its inner end adjacent the lock with a ledge forming a lock set seat, the lock when moved to unlocked position by the lifter being adapted to 75 tilt to a position permitting it to seat upon said ledge, the lifter being provided with means for cooperating with the coupler head to prevent accidental unlocking of the lock and also being provided with means adapted to engage and actuate the knuckle opener. 80

In testimony whereof I affix my signature.

WILLIAM McCONWAY, Jr.
